UNITED STATES PATENT OFFICE.

GEORGE WILLIAM SWIFT, JR., OF BORDENTOWN, NEW JERSEY.

ROTARY SHEARING MECHANISM.

1,034,164.

Specification of Letters Patent.

Patented July 30, 1912.

Application filed January 27, 1910. Serial No. 540,302.

To all whom it may concern:

Be it known that I, GEORGE W. SWIFT, Jr., of Bordentown, in the State of New Jersey, have invented a certain new and useful Improvement in Rotary Shearing Mechanism, whereof the following is a specification, reference being had to the accompanying drawings.

My invention relates to means for variably determining the length of sheets cut from a web of fabric and as hereinafter described includes means for progressing a web of fabric—for instance paper—in combination with a pair of rotary shears and adjustable means for varying the operation thereof in relation to the web feeding means. Said adjustable means includes a gear carrying a clutch member and arranged to be continuously rotated upon one of the rotary shear shafts in definite invariable relation with the paper feeding mechanism but normally loose upon said shaft and only clutched to turn it at intervals predetermined by a cam which is actuated by a train of gears in changeable relation with the paper feeding mechanism; the arrangement being such that said rotary shears are rendered inoperative after each shearing operation and remain inoperative until rendered operative by said cam controlling said clutch.

My invention includes the various novel features of construction and arrangement hereinafter more definitely specified.

In the drawings:—Figure I is a side view of the discharge end of a machine for facing corrugated paper, showing a convenient embodiment of my invention applied thereto. Fig. II is a fragmentary plan view, showing the changeable gear connecting the web feeding mechanism with the shearing mechanism. Fig. III is a right hand side view of the shearing mechanism as shown in Fig. I. Fig. IV is a fragmentary elevation of the left hand end of the shearing mechanism shown in Fig. III. Fig. V is a sectional view, taken on the line V, V in Fig. III. Fig. VI is a sectional view, taken on the line VI, VI in Fig. III. Fig. VII is a view similar to Fig. III but showing only a portion of the right hand end thereof on a larger scale. Fig. VIII is a right hand end view of the mechanism shown in Fig. VII. Fig. IX is a plan view of the mechanism shown in Figs. VII and VIII. Fig. X

is a sectional view of said mechanism, taken on the line X, X in Figs. VIII and IX.

My invention includes the various novel features of construction and arrangement hereinafter more definitely specified.

In said figures; the side frames 1 support the web feeding mechanism including the rotary drums 2 and 3 having the shafts 4 and 5 and carrying the belts 6 and 7 which are caused to grip the web 8 between their proximal runs, by the guide rollers 9 and 10, the latter being movable toward the former. Said paper feeding mechanism is arranged to be constantly operated by the main driving shaft 11 having the gear 12 engaging the gear 13 on said drum 3; the latter having the gear 14 connected by the gears 15 and 16 with the gear 18 on the drum 2. Said gears 15 and 16 are respectively engaged with the gears 20 and 21 carried by the guide rollers 9 and 10 so that said drums 2 and 3 and guide rollers 9 and 10 are rotated at the same peripheral speed to continuously progress said belts 6 and 7 and the web of fabric 8 extending between them to the rotary shearing mechanism which is supported by the standards 23 on said frames 1. Said shearing mechanism includes the parallel shafts 25 and 26 which, as shown in Figs. III to VI inclusive, carry opposite blades 28 respectively connected with said shafts 25 and 26 by lever arms 29, adjustably clamped in rigid relation with their respective shafts, by the bolts 30. As shown in Figs. III to VI inclusive, said arms 29 on the respective shafts 25 and 26 are rigidly connected with the bars 32 by bolts 33; said bars being co-extensive with said blades 28, and adjustably connected therewith by bolts 34, which draw the blades against the bars, and set screws 35 which thrust the blades away from said bars; whereby said blades may be adjustably flexed transversely with respect to their planes and be maintained in rigid relation with said bars. It is to be understood that by suitable adjustment of said bolts 34 and set screws 35, said blades 28 may be so set in relation to each other as to cut uniformly throughout their length, regardless of irregularities due to defects in grinding or wear of the cutting edges.

As shown in Fig. III, said rotary shear shaft 25 is provided with the gears 37 and 38, which are rigidly connected therewith

and respectively engaged with the gears 39 and 40 which are adjustable on said shaft 26, so that the blades 28 may be turned in precisely predetermined relation. To this end the shaft 26 is provided with the disk 42 which is stationary thereon but adjustably connected with said gear 39 by the bolts 43 which extend through the slots 44 into said gear. Said gear 39 is provided with the stud 45 which extends between the opposed set screws 46 carried by said disk 42 as shown in Fig. IV, and provided with jam nuts 47, the arrangement being such that the circumferential position of said gear 39 on the shaft 26 may be precisely determined by the adjustment of said set screws 46 when said bolts 43 are loose, and, said gear may then be rigidly clamped in adjusted position on said shaft 26, by said bolts 43. The gear 40 shown at the right hand side of Fig. III, and in Fig. VI is adjustably connected with said shaft 26 by bolts 49 which extend through the slots 50 in the disk 51 which is stationary on said shaft. Said shaft 26 is also provided with the collar 52 encircled by the spring-brake 54 which is supported by the bracket 55 connected with the aforesaid standard 23; whereby said shafts 25 and 26 are prevented from turning accidentally. Said shafts 25 and 26 are turned in predetermined definite relation to each other to effect the shearing operation, by positive rotation of said shaft 25 which is controlled as follows:—As best shown in Fig. X, said shaft 25 is reduced in diameter at the right hand end thereof, shown in Figs. II and X, and provided with the end collar 57 which is stationary thereon. The gear 59 which is loose on said shaft 25 is arranged to be constantly driven by the gear 60 on the shaft 61, which is constantly driven by said gear 14 in definite relation with the paper feeding mechanism. Said gear 59 carries the circular clutch ratchet 70 in operative relation with the reciprocating clutch pawl 71 carried by the collar 72 which is stationary on said shaft 25, and the arrangement is such that said shaft 25 is turned by the gear 59 only when the latter is connected therewith by the engagement of said pawl 71 in said ratchet 70 under pressure of the pawl spring 73, as shown. Otherwise, said gear 59 is continuously idly rotated in definite relation with the paper feeding mechanism while the shearing mechanism remains stationary; said clutch mechanism being automatically disengaged and the shearing mechanism left in stationary position at the end of each shearing operation. Such disengagement is effected by the cam slide 74 which extends in the circumferential groove 75 in said collar 72 and is there inclined as indicated by the dotted lines 76 in Fig. IX so as to enter the recess 78 in the pawl 71 and retract the latter clear of said

ratchet 70, whenever said collar 72 is turned to present said pawl recess 78 in registry with said cam slide 74 while the latter is upheld in said collar groove 75 as in Fig. X. Said pawl 71 can only be released to engage the clutch 70 and thus effect the rotation of the shaft 25 by the gear 59, when said slide 74 is lowered from the position shown in Fig. X, to clear the recess 78 in said pawl 71, and, such movement of said cam slide 74 is automatically effected, at predetermined times, by the face cam 80 having the groove 81 engaging the roller 82 on said slide 74 as shown in Fig. VIII. Said cam 80 is constantly rotated in definite but variable relation with the web feeding mechanism, being rigidly mounted on the shaft 84, which as shown in Fig. II has at its opposite end the gear 85 engaging the gear 86 on the shaft 87 extending between said shaft 84 and the shaft 5 of the drum 3 and having on its outer end the gear 89 which is operatively connected with said drum shaft 5 by gearing which is changeable to rotate said shaft 87, and consequently the cam 80, at different speeds while said shaft 5 is rotated at constant speed. As shown in Figs. I, II and III; the changeable gearing connecting said shaft 87 with the drum shaft 5, includes the gear 90 which engages the gear 89 on said shaft 87 and carries the gear 91 engaging the gear 92 on said shaft 5. Said gears 90 and 91 are carried by the stud shaft 94 which is radially adjustable in the slot 95 of the bracket 96, being rigidly connected with the latter in adjusted position by the nut 97 at the inner end of said shaft 94. Said bracket 96 being hung on the shaft 87, which turns loosely therein, is rigidly secured in connection with the frame 1, by the bolt 100 which extends through the slot 101 in said frame and is provided with the nut 102 shown in Fig. III on the inner side of said frame. It is to be understood that said stud shaft 94 may be adjusted both radially toward and away from said shaft 87 and toward and away from said shaft 5, to support gears of different sizes in operative relation with the gear 92 which may also be of various sizes; so that said cam 80 may be rotated at any desired ratio with the rotation of said shaft 5 of the drum 3 of the web feeding mechanism, and thus effect the shearing of the web 8 to form sheets of different lengths.

The mechanism above described operates as follows:—The web 8 being progressed between the blades 28 at constant speed, by the belts 6 and 7 carried by said drums 2 and 3, and, the gear 59 being rotated at constant speed in connection with said web feeding mechanism, as described, and, the clutch pawl 71 being engaged with the ratchet 70, as shown in Figs. IX and X; the shafts 25 and 26 are turned to bring the

blades 28 together as shown in Fig. III, to cut a sheet 108 from said web 8 as shown at the right hand side of Fig. I. Said blades 28 are then separated by the continued rotation of said shafts 25 and 26 in the direction of the arrows marked thereon in Fig. I, until the recess 78 in said pawl 71 is engaged by the inclined inner end 76 of the cam slide 74 which retracts said pawl 71 from the 5 ratchet 70 when said pawl is vertically beneath the shaft 25. The shearing mechanism being thus disengaged from said gear 59 is instantly stopped by the brake 54, while the gear 59 continues to rotate idly 10 until said face cam 80 is turned by the changeable gear mechanism aforesaid so as to lower said slide 74 by its roller 72 in the cam groove 81, and thus withdraw said slide 74 from engagement in the recess 78 of said 15 pawl 71. Whereupon, the spring 73 returns said pawl 71 into engagement with said ratchet 70 on the constantly rotating gear 59 and rotation of said cam shafts 25 and 26 is resumed to effect another shearing operation as above described.

I do not desire to limit myself to the precise details of construction and arrangement herein set forth, as it is obvious that various modifications may be made therein without departing from the essential features of my invention as defined in the appended claims.

I claim:

1. The combination with web feeding mechanism; of two parallel rotary shear shafts; lever arms adjustable on said shafts; bars extending parallel with said shafts and respectively rigidly connected with the arms on the respective shafts; shear blades carried by said bars; bolts arranged to draw 35 said blades toward said bars; set screws arranged to thrust said blades away from said bars; gears operatively connecting said shafts; one of said gears having means arranged to circumferentially adjust it, including a disk stationary on its shaft and having opposed set screws, and a stud projecting from said adjustable gear between said set screws; clutch mechanism whereby said shafts may be alternately rotated and 40 released, including a gear mounted to turn loosely on one of said shafts and having a face ratchet; a collar, stationary on that shaft, carrying a reciprocating pawl arranged to engage said ratchet; a spring 45 tending to thrust said pawl into said ratchet; a cam slide supported independently of said clutch; means arranged to reciprocate said cam slide, including a face cam having a groove in which a roller on 50 said slide is engaged; and, means arranged to changeably rotate said face cam, including changeable gears connecting said web feeding mechanism with said face cam shaft.
2. The combination with web feeding 65 mechanism; of two parallel rotary shear
3. The combination with web feeding mechanism; of two parallel rotary shear 85 shafts; bars extending parallel with said shafts and respectively rigidly connected therewith; shear blades carried by said bars; means arranged to adjustably connect said blades with said bars; gears operatively connecting said shafts; clutch mechanism whereby said shafts may be alternately rotated and released, including a gear mounted to turn loosely on one of said 90 shafts and carrying a ratchet; a pawl carried by said shaft arranged to engage said ratchet; a spring tending to thrust said pawl into said ratchet; a cam supported independently of said clutch, arranged to automatically disengage the latter; and, means operatively connecting said web feeding mechanism with said cam.
4. The combination with web feeding mechanism; of two parallel rotary shear 105 shafts; shear blades carried by said shafts; gears operatively connecting said shafts; clutch mechanism whereby said shafts may be alternately rotated and released, including a gear mounted to turn loosely upon one of said shafts and carrying a ratchet; a pawl carried by said shaft, arranged to engage said ratchet; a cam arranged to automatically disengage said clutch, and, means operatively connecting said web feeding 110 mechanism with said cam.
5. The combination with web feeding 120 mechanism; of two parallel rotary shear shafts; lever arms circumferentially adjustable on said shafts; bars extending parallel with said shafts and respectively rigidly connected with the arms on the respective shafts; flexible shear blades carried by said bars; bolts arranged to draw said blades toward said bars, transversely with respect to the planes of said blades; set screws arranged to thrust said blades away from said bars, transversely with respect to the planes of said blades; and, means co-operatively connecting said shafts; whereby, 125 said blades may be adjustably flexed trans-

versely with respect to their planes and be maintained in rigid relation with said bars.

6. The combination with web feeding mechanism; of two parallel rotary shear shafts; bars extending parallel with said shafts and respectively rigidly connected therewith; flexible shear blades carried by said bars; bolts arranged to draw said blades toward said bars, transversely with respect to the planes of said blades; set screws arranged to thrust said blades away from said bars, transversely with respect to

the planes of said blades; and, means coöperatively connecting said shafts; whereby, said blades may be adjustably flexed transversely with respect to their planes and be maintained in rigid relation with said bars. 15

In testimony whereof, I have hereunto signed my name at Bordentown, New Jersey, this eleventh day of January 1910.

GEORGE WILLIAM SWIFT, JR.
